CLAIM

The ornamental design for a footwear as shown and described.

DESCRIPTION

FIG. 1 is a front, top and left side perspective view of an embodiment of a footwear according to the new design; FIG. 2 is a front side elevation view thereof;

FIG. 3 is a back side elevation view of the surface pattern thereof;

FIG. 4 is a left side elevation view of the surface pattern thereof;

FIG. 5 is a right side elevation view thereof;

FIG. 6 is a top plan view thereof;

FIG. 7 is a bottom plan view thereof; and,

FIG. 8 is a back, bottom, and right side perspective view thereof.

The broken lines in the drawings show portions that form no part of the claimed design. The dot dash lines represent bounds of the claimed design and form no part thereof.

1 Claim, 8 Drawing Sheets
